UNITED STATES PATENT OFFICE.

CHARLES F. DAUSMANN, OF GLENDALE, NEW YORK, ASSIGNOR TO THE PRISMATONE CO., INC., OF CHICAGO, ILLINOIS, A CORPORATION OF NEW YORK.

MACHINE FOR REGISTERING CARBON-TISSUE SHEETS UPON COPPER PRINTING CYLINDERS.

Application filed June 8, 1923. Serial No. 644,110.

To all whom it may concern:

Be it known that I, CHARLES F. DAUSMANN, a citizen of the United States, and a resident of Glendale, county of Queens, 5 and State of New York, have invented certain new and useful Improvements in Machines for Registering Carbon-Tissue Sheets upon Copper Printing Cylinders, of which the following is a specification.

10 This invention relates to a machine for applying carbon tissue sheets to copper cylinders and has for its primary object to provide a simply constructed machine for facilitating the accurate register and application of the 15 carbon tissue sheets upon which the prints to be etched into the surface of the cylinder are delineated, to the surface of the cylinder. More particularly, I propose to provide 20 a machine for this purpose having an adjustably mounted pressure roller for firmly pressing the carbon tissue upon the periphery of the printing cylinder as the latter is rotated and a plurality of adjustable gauge members for initially engaging the end of 25 the tissue sheet to hold the same in position upon the surface of the cylinder whereby the prints of several sheets will be properly registered or alined, regardless of the number of cylinders in the color press.

30 It is also another object of the invention to provide an improved arrangement of adjustable supports for accommodating cylinders of various lengths, said supports having anti-friction bearings at their opposite 35 ends upon which the cylinder shaft is adapted to be disposed. The pressure applying means is mounted above one end of the cylinder supports while at the other end thereof a container for a developing 40 bath is arranged. Therefore, after the carbon tissue sheets have been registered and applied to the surface of the cylinder the ends of the cylinder shaft may be rolled along the supports to the bearings at the 45 opposite ends thereof so that by rotation of the cylinder in the latter position the tissue sheets can be immersed in the developing bath.

50 It is also a further general object of the invention to provide a machine for the above purpose which is of comparatively simple construction, not liable to get out of

order and which may be easily operated with relatively little manual labor.

With the above and other objects in view, 55 the invention consists in the improved machine for registering and applying carbon tissue sheets to cylinders and in the form, construction and relative arrangement of its several parts as will be hereinafter more 60 fully described, illustrated in the accompanying drawings and subsequently incorporated in the subjoined claims.

In the drawings wherein I have illustrated one practical and satisfactory embodiment of the invention and in which similar reference characters designate corresponding parts throughout the several views;

Figure 1 is an end elevation of a machine constructed in accordance with one embodiment of my invention;

Figure 2 is a rear side elevation thereof, parts being broken away and others shown in section;

Figure 3 is an enlarged detail end elevation of the adjustable tissue sheet applying means;

Figure 4 is a top plan view thereof;

Figure 5 is a detail view of one of the carbon tissue sheets.

In the art of intaglio photogravure printing, copper is electro-deposited upon the cylinder. This copper coating is ground down and provided with a very highly polished surface. Sheets of carbon tissue 85 upon which the matter to be printed is delineated are then applied to the copper surface of the cylinder and such carbon sheets subsequently subjected to the action of an etching fluid whereby the impressions of the carbon sheets are etched into the surface of the cylinder. Heretofore considerable difficulty has attended the accurate registration and application of the carbon tissue sheets to the surface of the cylinder, such operation 90 being not only quite laborious and time-consuming but also not infrequently resulting in the misalignment or improper spacing of the prints on the different carbon sheets in relation to each other either longitudinally or circumferentially of the printing cylinder. My present invention remedies this difficulty and provides a machine 95 which may be easily operated and which

80

will greatly facilitate the registration and application of the carbon sheets to the surface of the cylinder with absolute assurance of the accurate registration or alignment of the prints.

In the embodiment of the invention illustrated in the accompanying drawings, I have shown the machine as provided with a base frame 5. The frame 5 includes similar end members which are connected at their upper ends by parallel longitudinally extending channel beds 6. Upon the opposite ends of one of these beds the bearing standards or uprights 7 are bolted or otherwise rigidly fixed. Each of these channel beds is provided with longitudinally extending guide rails 8 between which the angular foot 9 of a casting is slidably engaged. These slideable castings are arranged in pairs, the castings in each pair being rigidly connected by a bar 10 which forms a continuation of the lateral extensions 11 of said castings. These extensions are slotted to receive spaced rollers 12 upon which the opposite ends of the shaft 8 of the cylinder C are rotatably supported.

The foot 9 of each of the sliding castings is provided upon its underside with a threaded sleeve or nut 13. In suitable bearings at the opposite ends of each of the channel beds 6 of the frame structure the ends of the shafts 14 are journaled. These shafts have right and left hand threaded portions engaged with the similarly threaded bores of the sleeves 13 on the sliding cylinder supports at opposite ends of the machine. One of the shafts 14 is provided at one end with a hand wheel 15, the other end of this shaft being connected by means of suitable gearing 16 to a transverse shaft 17, said shaft in turn being connected by similar gearing 18 to the other of the shafts 14. Thus upon turning the hand wheel 15, the two shafts 14 are simultaneously rotated in the same direction to move the supports for the cylinder towards or from each other, as the length of said cylinder may require.

In the upper ends of the bearing standards 7, the ends of a longitudinally disposed shaft 19 are journaled. Upon this shaft parallel beams 20 are rigidly fixed intermediate of their ends. These beams at one of their ends are rigidly connected to each other by a bar 21 and in said ends of the beams a presser roll 22 is rotatably mounted. In spaced relation to this roll a shaft 23 is journaled in the beams 20 and upon said shaft adjacent each end thereof an arm 24 is rigidly fixed. These arms are curved and extend over and forwardly of the roller 22 as clearly shown in Figure 1 of the drawings. Between the forward end of said arms a rectangular bar 25 is rigidly fixed. To the underside of said bar and extending the full length thereof a laterally projecting metal plate 26 is fixed by means of the screws 27 and is provided with

a beveled edge 28. A plurality of gauge members 29 are adjustable along the bar 25 and may be conveniently fixed in adjusted position by suitable set screws 30. Each of these gauge members has a spring extension 31 overlying the beveled edge 28 of the plate 26 for a purpose which will presently appear.

To the shaft 23 a lever 32 is secured at one of its ends, said lever also extending forwardly over the roller 22 and carrying an adjustable stop screw 33 adapted to engage the bar 21 and thus limit the turning movement of shaft 23 in one direction and the downward movement of the forward ends of arms 24 with respect to the roller 22. To one end of the shaft 23 a collar having a detent 34 is suitably secured, said detent being adapted to engage a shoulder 36 on the lever 35 which is pivotally mounted at one of its ends upon one of the beams 20. A spring 37 connected to the other end of said lever holds the lever in a normal position as seen in Figure 3 of the drawings. Thus it will be clear that when the lever 32 is lifted to elevate the arms 24 and raise the gauge devices from their operative positions in proximity to the surface of the cylinder, the detent 34 will engage the lower edge of the lever 35 and lift the same slightly against the action of spring 37 until said detent catches behind the shoulder 36 of the lever. Thus the lever will sustain this gauge means in the raised or inoperative position while the cylinder is being rotated to cause the roller 22 to firmly press the carbon sheet on the surface of the cylinder.

To one end of the shaft 19 a worm gear 38 is secured and is engaged by the worm 39 mounted upon a bracket 40 on the upper end of one of the standards 7, said worm being turned by a suitable hand wheel 41. The rim of this wheel may be provided with suitable graduations with respect to which an index member 42 fixed to the bearing standard is positioned. Thus by rotating the hand wheel 41 to the extent indicated by the graduations, the beams 20 may be rocked so as to position the presser roll 22 above the ends of the adjustable cylinder supports as required for cylinders which print in different colors and in order to apply the same pressure to the carbon sheets on different cylinders.

The other ends of the beams 20 are rigidly connected by the rod 43 which serves to partially counterbalance the tissue sheet applying mechanism arranged upon the other ends of said beams.

At the rear side of the machine frame a trough 44 is supported upon suitable spaced brackets 45 and to the bottom thereof the drain pipe 46 is connected. Within this trough a sheet metal pan or container 47 for the developing and sizing bath is suitably

mounted, said pan extending between the longitudinally adjustable cylinder supports and in position to receive the lower portion of the cylinder when it is moved from one end of said supports at the front side of the machine to the opposite ends thereof at the rear side of the machine.

In Figure 5 of the drawings I have illustrated a carbon tissue sheet T upon which the matter to be printed indicated at t, is delineated. In the upper right and left hand corners of this sheet an incision T' is made and these incisions in all of the carbon tissue sheets to be registered and applied to the different color cylinders, are placed at precisely the same distance from the longitudinal and end edges of the sheet. In the operation of the machine the edge portion of the carbon sheet having the incisions therein is placed upon the peripheral face of the cylinder which has been mounted upon the forward ends of the adjustable supports as shown in Figure 1 of the drawings. The gauge members 29 are adjusted along the bar 25 and the edge of the sheet is manipulated until the spring fingers 31 of said gauge members engage in the cuts or incisions T' in the tissue sheet. A series of the tissue sheets may thus be positioned along the length of the cylinder and after the gauge devices have been properly positioned in the incisions of each sheet, a suitable adhesive composition is applied to the edge of the sheet so that it is retained upon the face of the cylinder. The other end of the sheet may be conveniently supported by engaging the same in a suitable clamp 48 on one end of a flexible member 49 passing over a sheave 50, a weight 51 being attached to the other end of said flexible member, as shown in Figure 1 of the drawings. The lever 32 is now moved upwardly until the detent 34 engages the shoulder of lever 35 as above explained, so that the gauge means is held in an elevated position. The hand lever 52 is now attached to one end of the cylinder shaft S and said cylinder is rotated upon the bearing rollers 12. The carbon tissue sheet is thus moved beneath the presser roll 22 and is thereby caused to firmly adhere to the peripheral surface of the cylinder. Other tissue sheets may then be applied in a similar manner until the surface of the cylinder is entirely covered. By reason of the adjustable gauge devices and the incision T' in the corners of the tissue sheets with which they engage, the accurate application of the successively applied sheets is assured so that there will be precise alignment or registration of the prints upon said sheets both circumferentially and longitudinally of the cylinder. After all of the tissue sheets have been applied, the ends of the cylinder shaft are lifted from engagement upon the bearing rollers 12 and said

shaft is rolled along the spaced adjustable supports, only the shaft ends engage upon the other bearing rollers 12 mounted in the opposite or rear ends of the supports. The lower side of the cylinder having the tissue sheets thereon is thus positioned in the developing and sizing bath in the pan 47 so that by now again rotating the cylinder, all of the carbon tissue sheets on the surface thereof may be immersed in said bath.

From the foregoing description considered in connection with the accompanying drawings, the construction, manner of operation and several advantages of the improved machine will be clearly understood. It will be apparent that by reason of my invention, much manual labor as heretofore required in the registration of the carbon tissue sheets upon such cylinders may be obviated. Also, loss of time and destruction of the tissue sheets due to their inaccurate application to the cylinder surface is avoided. The machine as a whole is of comparatively simple construction, may be easily operated and will very materially expedite the execution of the process of photogravure printing as heretofore practiced in the art.

While I have herein shown and described an embodiment of the improved machine which I have found very satisfactory in practical use, it is nevertheless to be understood that such machine is susceptible of embodiment in various other alternative constructions and I accordingly reserve the privilege of resorting to all such legitimate changes in the form, proportion and relative arrangement of the several parts as may be fairly embodied within the spirit and scope of the invention as claimed.

I claim:

1. In combination, means for rotatably supporting a cylinder, a presser roll in superposed relation to the cylinder, and means for retaining the end of the carbon tissue sheet in adjusted position upon the surface of the cylinder in advance of said presser roll.

2. In combination, means for rotatably supporting a cylinder, a presser roll to firmly press a carbon tissue sheet upon the surface of the cylinder, and adjustable gauge devices arranged in advance of the presser roll to engage index means on one end of the tissue sheet and retain the end of said sheet in adjusted position upon the surface of the cylinder.

3. In combination, means for rotatably supporting a cylinder, a pivotally mounted frame, a presser roll journaled in said frame, means for adjusting the frame to position the presser roll upon the cylinder, and means carried by said frame to engage the end of a carbon tissue sheet and retain the same in adjusted position upon the surface of said cylinder in advance of the presser roll.

4. In combination, means for rotatably supporting a cylinder, a pivotally mounted frame, a presser roll journaled in said frame, means for adjusting the frame to position the presser roll upon the cylinder, and a plurality of adjustable gauge devices carried by said frame for engagement with index means on the end of the carbon tissue sheet to retain the end of the sheet in adjusted position upon the surface of said cylinder in advance of the presser roll.
5. In combination, means for rotatably supporting a cylinder, a pivotally mounted frame, a presser roll journaled in said frame, means for adjusting the frame to position the presser roll upon the cylinder, means movably mounted in said frame to engage the end of a carbon tissue sheet and retain the same in adjusted position upon the surface of said cylinder in advance of the presser roll, and means to support said sheet engaging means in an inoperative position in the frame when the cylinder is rotated.
6. In combination, means for rotatably supporting a cylinder, a frame, a presser roll journaled in said frame for engagement upon the periphery of the cylinder, means movably mounted in said frame to engage the end of a carbon tissue sheet and retain the same in adjusted position upon the surface of said cylinder in advance of the presser roll, and means to support said sheet engaging means in an inoperative position in the frame when the cylinder is rotated.
7. In combination, means for rotatably supporting a cylinder, a frame, a presser roll journaled in said frame for engagement upon the periphery of the cylinder, spaced arms pivotally mounted at one of their ends in the frame and projecting forwardly of the presser roll, a bar mounted in the other ends of said arms, and a plurality of adjustable gauge members adapted to engage the end of the carbon tissue sheet to retain the same in adjusted position upon the surface of the cylinder.
8. In combination, means for rotatably supporting a cylinder, a frame, a presser roll journaled in said frame for engagement upon the periphery of the cylinder, spaced arms pivotally mounted at one of their ends in the frame and projecting forwardly of the presser roll, a bar mounted in the other ends of said arms, a plurality of adjustable gauge members adapted to engage the end of the carbon tissue sheet and retain the same in adjusted position upon the surface of the cylinder, and means for supporting said arms and the gauge members in an elevated position in said frame when the cylinder is rotated.
9. In combination, means for rotatably supporting a cylinder, a pivotally mounted frame, a presser roll journaled in said frame for engagement upon the periphery of the cylinder, means carried by said frame to engage the end of a carbon tissue sheet and retain the same in adjusted position upon the surface of the cylinder in advance of the presser roll, and means for rocking said frame to move the presser roll and the sheet positioning means into or out of operative relation to the cylinder.
10. In combination, means for rotatably supporting a cylinder, a pivotally mounted frame, a presser roll journaled in said frame for engagement upon the periphery of the cylinder, means carried by said frame to engage the end of a carbon tissue sheet and retain the same in adjusted position upon the surface of the cylinder in advance of the presser roll, means for rocking said frame to move the presser roll and the sheet positioning means into or out of operative relation to the cylinder, and additional means for adjustably positioning said sheet engaging means independently of the presser roll and with respect to said frame.
11. In combination, means for rotatably supporting a cylinder, a frame, a presser roll journaled in the frame for engagement upon the periphery of the cylinder, a shaft mounted in said frame, spaced arms fixed at one of their ends to the shaft and extending in advance of the presser roll, a plurality of adjustable gauge members mounted between the other ends of said arms and adapted to engage index means on the end of the carbon tissue sheet and retain the same in adjusted position upon the surface of the cylinder, a spring-held lever pivotally mounted in the frame, means for rocking said shaft to dispose the gauge members out of operative relation to the cylinder, and a detent member fixed upon the shaft and adapted to be engaged by said lever to sustain the gauge members in an inoperative position.
12. In combination, spaced supports, roller bearings mounted upon the opposite ends of each support adapted to rotatably support the ends of a cylinder shaft, means mounted above one end of the supports for applying carbon tissue sheets to the surface of the cylinder when the latter is rotated, and a pan arranged beneath the opposite ends of said supports to contain a developing bath, the cylinder shaft adapted to be moved along said supports and positioned upon the roller bearings at the latter ends thereof whereby upon rotation of the cylinder the carbon sheets thereon will be immersed in the developing bath.
13. In combination, spaced slidably mounted supports, means for moving said supports towards and from each other, roller bearings mounted upon the opposite ends of each support and adapted to rotatably support the ends of a cylinder shaft, means mounted above one end of the supports for

applying carbon tissue sheets to the surface of the cylinder when the latter is rotated, means for adjusting said sheet applying means into and out of operative relation to the cylinder, a pan arranged beneath the opposite ends of said supports to contain a developing bath, the cylinder shaft adapted to be moved along said supports and positioned upon the roller bearings at the latter ends thereof whereby upon rotation of the cylinder the carbon sheets thereon will be immersed in the developing bath.

14. In combination with means for rotatably supporting a cylinder, gauge means adapted to be engaged with index means on the end of a carbon tissue sheet to hold said sheet in an adjusted position upon the peripheral surface of the cylinder prior to the rotation of said cylinder.
15. In combination with means for rotatably supporting a cylinder, a presser roll adapted to press a carbon tissue sheet upon the peripheral surface of the cylinder in the rotation thereof, means adapted to be engaged with an end of the carbon tissue sheet to releasably hold said sheet end in adjusted position on the surface of the cylinder prior to the rotation thereof, and means for mounting said sheet holding means for movement into and out of operative relation to the cylinder surface independently of the pressure roll.
16. In combination with means for rotatably supporting a cylinder, a presser roll to firmly press a carbon tissue sheet upon the peripheral surface of said cylinder in the rotation thereof, a pivotally mounted frame, a plurality of gauge devices carried by said frame adapted to engage the end of a carbon tissue sheet to releasably hold the same in adjusted position upon the surface of the cylinder prior to the rotation thereof, and means for supporting said frame against swinging movement with the gauge devices disposed in an inoperative position relative to the cylinder during the rotation of the latter.

17. In combination, spaced supporting bearings for a cylinder shaft and guide rails extending between said bearings to support the cylinder shaft for rolling movement from one of the supporting bearings to the other, means for applying carbon tissue sheets upon the peripheral surface of the cylinder when the latter is mounted upon the bearings at one end of said guide rails, and a container for a development bath arranged at the other end of the guide rails whereby, when the cylinder with the carbon tissue sheets thereon is positioned upon the other bearings at the latter ends of the rails, said sheets upon rotation of the cylinder are immersed in the developing bath.

In testimony that I claim the foregoing as my invention, I have signed my name hereunder.

CHARLES F. DAUSMANN.
